UNITED STATES PATENT OFFICE.

CHARLES E. DURYEA, OF ST. LOUIS, MISSOURI, ASSIGNOR OF ONE-HALF TO
RICHARD GARVEY, OF SAME PLACE.

BICYCLE-SADDLE.

SPECIFICATION forming part of Letters Patent No. 293,725, dated February 19, 1884.

Application filed December 3, 1883. (No model.)

To all whom it may concern:

Be it known that I, CHARLES E. DURYEA, of St. Louis, in the county of St. Louis and State of Missouri, have invented certain Improvements in Bicycle-Saddles, of which the following is a specification.

The object of this invention is to provide a light and elastic saddle the tension of which may be readily controlled, and which may be applied with facility to existing machines and adjusted forward and backward thereon at pleasure.

It is also a further object of the invention to produce a saddle which shall be free from the ordinary liability, which exists in adjustable saddles, of the parts becoming loosened by the vibration of the machine so as to move out of position.

To this end it consists, essentially, in a flexible seat or saddle having its two extremities attached to an elastic supporting-frame composed, essentially, of two longitudinal parallel springs arranged in such manner as to admit of their passing downward on opposite sides of the backbone or reach, and of their maintaining a longitudinal strain or tension to the seat.

It also consists in the frame constructed of a single piece of metal doubled or bent into the form hereinafter described.

It also consists in clips or fastening devices of peculiar construction, adapted to secure the elastic frame to the backbone.

Referring to the accompanying drawings, Figure 1 represents a side elevation of a portion of a bicycle having my saddle applied thereto. Fig. 2 is a top plan view of the same. Fig. 3 is a cross-section on the line *xx*. Fig. 4 represents a perspective view of the saddle in an inverted position.

Referring to the accompanying drawings, A represents the front steering and driving wheel of an ordinary bicycle; B, the swiveling fork in which the wheel is mounted, and which is provided with the steering-bar; and C, the backbone or reach, the forward end of which is swiveled or journaled to the fork, as shown, while the rear end is adapted to receive the rear wheel. All of the foregoing parts are

constructed in the ordinary manner, and constitute no part of my invention, which relates solely to the construction of the saddle and fastening devices.

My saddle consists, as most plainly represented in Fig. 2, of a flexible seat or saddle proper, D, and of the supporting-spring E, attached to the two extremities thereof.

The seat or saddle proper consists of a sheet of leather, canvas, or equivalent pliable material, which may be given, as represented in the drawings, essentially the same form or outline as saddles now in common use—that is to say, a decreasing width from the rear end to the front, or modified at will.

The supporting-spring E is preferably constructed, as represented, of a single rod or bar of steel, doubled or bent into the peculiar form shown. At its forward end the spring has a horizontal portion, *a*, to receive and sustain the forward end or neck of the seat, which is preferably looped around the same and secured by rivets, as shown. From the two ends of the portion *a* the spring is extended downward, forming the upright arms *b*, and bent thence backward in a substantially horizontal direction to a point near the rear end of the saddle, where they are curved upward and attached to the under side of a plate, *e*, riveted or otherwise secured firmly to the under side of the seat. This plate *e* is made of a form corresponding with that of the rear end of the saddle, whatever it may be. The ends of the spring may be attached to the plate, and the plate attached to the seat in any suitable manner.

It is preferred to bend the rear ends of the spring upward in a horizontal direction, to give them a broad and firm bearing against the under side of the plate and to pass the rivets downward through the seat, the plate, and the arms, as shown, one set of rivets thus serving to hold the three parts firmly together.

In making use of my saddle, the spring-arms are dropped downward on opposite sides of the backbone, as represented in the drawings, thus bringing the saddle proper in position directly over the backbone and behind the steering-head, as required. The springs may be attached firmly to the backbone in any suit-

able manner; but for various reasons I prefer to make use of the fastening-clips represented in the drawings. These fastenings consist of U-shaped clips or stirrups *f*, adapted to fit transversely on the upper side of the backbone, with their ends turned outward to engage beneath the two springs to give support thereto, and of corresponding clips, *g*, adapted to fit transversely upon the under side of the backbone, with their ends extended laterally above the spring-arms and provided with set-screws *h*, to bear on said arms. There may be any desired number of the clips, and they may be located at any suitable points in the length of the springs, their location being adjustable at the will of the user, in order to regulate the tension of the springs or the position of the saddle. By adjusting the screws the springs may be drawn tightly upon the backbone and caused to engage firmly upon the spring-arms, so as to hold the saddle securely in position.

It will be observed that the spring-arms exert a longitudinal strain or tension upon the seat, which is permitted, however, to yield in a vertical direction when a weight is applied sufficient to overcome the tension of the rear ends of the arms. The short upright portions *b* are practically rigid, and, consequently, the seat is without any tendency to move in a forward or backward direction, its yielding movement being confined practically to a vertical direction. By shifting the clips forward and backward with respect to the spring-arms the seat may be given more or less elasticity.

When the clips are all located near the forward end of the spring-arms, it will be seen that the rear ends of the arms are free to rise and fall bodily, thus permitting the saddle to yield without the flexion of the seat. The adjustment of the clips toward the forward end of the arms also has the effect of increasing the length of the flexible portion, or portion which is free to yield, and thus to permit the seat to sink beneath a lighter weight.

It is to be observed as a peculiarity of my saddle that it may be adjusted forward and backward to and from the head of the machine without affecting its tension, and that, on the other hand, its location may be modified without varying its tension, these two independent adjustments being highly advantageous, in that they admit of the saddle being adjusted to riders of different weights and to tastes of different riders, some of whom prefer to have the saddle nearer the head than others.

It is manifest that the clips bearing screws may be applied to the top of the backbone and the others applied to the under side. If one set of clips be longer than the other, this reversibility will be found to be of advantage, in that it admits of the saddle being raised or lowered. It is also manifest that the screws may be applied to both the upper and the lower clips, as represented in dotted lines, and in this manner provision made for raising and lowering the saddle bodily.

I am aware that a flexible seat has been combined with a single supporting-spring, exerting a longitudinal strain thereon; but my construction differs therefrom and is superior thereto, in that my double spring may be applied to the two sides of the backbone, thus allowing the seat to be placed in close proximity to the backbone, instead of being raised an objectionable distance therefrom. The employment of the double springs is also advantageous, in that it enables me to secure the saddle the more firmly against lateral movement, and in that it admits of the saddle being raised and lowered upon the machine.

75

80

While it is preferred, as before stated, to construct the entire spring *E* of a single piece of metal, it is manifest that two spring-arms applied in the same relative positions may be connected at the forward end by a device of any suitable character adapted to sustain the forward end of the seat.

85

Having thus described my invention, what I claim is—

1. The improved saddle for a bicycle, consisting of a flexible seat or saddle proper, and a supporting-spring having two substantially parallel arms with upturned ends attached to the seat, and adapted, as described, to apply a longitudinal tension thereto.

95

2. In combination with the flexible seat of diminishing width toward its front end or neck, the supporting-spring consisting of a single elastic rod doubled and bent upon itself, and having its ends upturned and connected to the rear extremities of the seat, substantially as described.

3. In a bicycle-saddle, the combination of a flexible seat having a widened rear end, and a supporting-plate attached to the rear edge of the seat, and two parallel spring-arms attached to the plate, and extended thence downward and forward to the forward extremity of the seat.

105

4. In combination with the backbone of a bicycle, a flexible seat or saddle, two longitudinal springs located on opposite sides of the backbone and connected to the extremity of the seat, to maintain a longitudinal tension thereof, and means, substantially as described, connecting said springs with the backbone.

110

5. In combination with the backbone of a bicycle, a flexible seat or saddle, two spring-arms extending lengthwise of the saddle on opposite sides of the backbone and acting, as described, to strain the seat longitudinally, and clips or fastening devices adjustable longitudinally with respect to the backbone, whereby the saddle may be adjusted forward and backward without affecting its tension.

120

6. In combination with the backbone of a bicycle, clips or fastening devices applied thereto, and a saddle having two longitudinal springs connected to the extremities of the seat and adapted to strain the same longitudinally, said springs being adjustable longitudinally with respect to the clips, whereby the saddle may

125

130

be adjusted forward and backward and its tension or stiffness modified at the same time.

7. In combination with the backbone and two saddle-supporting arms on opposite sides thereof, the clips applied to the upper and lower sides of the backbone, and the adjusting-screws, applied substantially as shown.

8. In combination with a backbone and two saddle-supporting arms on opposite sides there-

of, clips applied to the top of the backbone to and engaging at their ends beneath the arms, and secondary clips applied beneath the backbone and engaging at their ends above the arms, as described.
